UNITED STATES PATENT OFFICE

MARIAN A. MATTHEWS, OF NEWBURGH, NEW YORK

SHARPENING DEVICE

Application filed February 18, 1930. Serial No. 429,422.

This invention relates to a sharpening device for knives and shear blades, and has for its object to provide, in a manner as hereinafter set forth, a device of the class referred to for efficiently and expeditiously sharpening a knife or shear blade when desired.

A further object of the invention is to provide, in a manner as hereinafter set forth, a device of the class referred to including means so constructed and arranged to overcome the cutting of low places or hollows in a knife or shear blade on removing notches or broken places in the cutting edge of the blade.

A further object of the invention is to provide, in a manner as hereinafter set forth, a sharpening device for the purpose referred to including means for adjusting it to enable the use thereof when sharpening a knife or shear blade of different thicknesses to insure for carrying of the proper bevel of the cutting edge.

A further object of the invention is to provide, in a manner as hereinafter set forth, a sharpening device of the class referred to including a set of pivotally supported cutting blades and adjustable guiding means to change the size of the cutting space for varying thicknesses of knife and shear blades whereby the cutting blades can act in an efficient manner for the purpose of sharpening the knife or shear blade.

A further object of the invention is to provide, in a manner as hereinafter set forth, a sharpener device for the purpose referred to including a set of pivotally supported cutting blades, each of oblong contour and with the mounting for such blades permitting of the four cutting edges of the latter being utilized their entire length.

Further objects of the invention are to provide, in a manner as hereinafter set forth, a sharpening device for the purpose referred to which is simple in its construction and arrangement, strong, durable adjustable, thoroughly efficient in its use, readily assembled, expeditiously set for sharpening purposes and comparatively inexpensive to manufacture.

With the foregoing and other objects in

view the invention consists of the novel construction, combination and arrangement of parts as hereinafter more specifically described, and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is a side elevation of a sharpening device in accordance with this invention.

Figure 2 is an end view thereof.

Figure 3 is a longitudinal sectional view of the device.

Figure 4 is an inverted plan of the upper retainer for the upper end of the set of cutting blades.

Figure 5 is a top plan view of the lower retainer for the lower end of the set of cutting blades.

Referring to the drawings in detail, 1 denotes a base member having a portion thereof of greater height than the remaining portion and such portion of greater height is indicated at 2 and provides a shoulder 3. The base 1 is of rectangular contour and the shoulder 3 extends lengthwise thereof and is disposed between the longitudinal center of the base 1 and one side edge thereof.

The base 1 is constructed of metal and has arranged upon its upper face, centrally thereof, a transversely extending retainer and fulcrum for the lower ends of a set of cutting or sharpening blades to be presently referred to. The combined retainer and fulcrum element is indicated generally at 4 and is formed on the low part 5 of the base 1. The element 4 provides a pocket 6 and the side walls of the latter are indicated at 7, 8 and the end walls at 9, 10. The pocket 6 is of substantially rectangular contour and is disposed transversely with respect to base 1. The end walls 10 are set up from two oppositely extending, inclined parts, which at the center thereof provides a fulcrum point 11. The parts of the wall 10 extend inwardly from the side walls 7, 8. The end wall 9 has its inner side disposed

at two opposite inclinations to provide a fulcrum point 12 which is arranged in alignment with the fulcrum point 11.

Mounted upon the part 5 of the base 1 is a pair of vertically disposed, inverted, yoke-shaped members referred to generally at 13, 14. The members 13, 14 are spaced a substantial distance from the element 4. Each of said members includes a bottom 15 and a pair 10 of side arms 16, 17 which are vertically disposed. The arms 17 abut against the shoulder 3 and project a substantial distance above the base 1. The bottom 15 of each member 13, 14 is slotted as at 18 and extending through base 15 and slots 18 are screws 19 carrying on the upper ends binding nuts 20. The arrangement referred to permits of the adjusting of the member 13 or 14 towards and from a side of the element 4 when occasion requires and for maintaining them in the position to which they have been adjusted.

The members 13, 14 provide supports for the shafts 21 of upstanding, adjustable, yoke-shaped guide members referred to generally 25 at 22, 23.

Each guide member includes a pair of side arms 24, 25 and a curved top 26. The guide members 22, 23 extend down into the members 13, 14 and project inwardly therefrom toward the element 4 and are further positioned above member 4. The inner lower corners of the guide members 22, 23 are positioned in superposed relation with respect to element 4. See Figure 3. Elements 22, 23 extend at an inclination with respect to the members 13, 14. The arms 24, 25 of each guide member at a point between the vertical median and outer edge thereof are provided with aligning openings for the passage 40 of a shaft 21. The arm 25 of each guide member is positioned against the inner face of an arm 17 of a member 13 or 14. The arm 24 of each guide member is positioned in spaced relation with respect to an arm 16 of a supporting member 13 or 14. The arms 16, 17 of each supporting member are formed with aligning openings, for the passage of the shafts 21 and the openings in the arms 16, 17 align with the openings in the arms 24, 25.

50 The shafts 21 are provided with sleeves 27. Each sleeve 27 is positioned between the arms 24, 25 of a guide member. Each shaft 21 carries a washer 28 which is interposed between the arm 24 of a guide member and the arm 16 of a supporting member. The shafts 21 are headed as indicated at 29 and abut against the outer faces of the arms 17 of the supporting members. The shafts 21 are also threaded as indicated at 30 and engaging with the threaded portions are binding nuts 31 which abut against the arms 16 of the supporting members. The sleeves 27 maintain the arms 24, 25 on the guide members permanently in spaced relation with respect to each other. The arms 24, 25 of the

guide members can be adjusted on the shafts 21 to various angular positions with respect to the arms of the supporting members 13, 14.

The guide members 22, 23 are releasably maintained in adjusted position by a bolt 32, 70 a nut 33 and with the bolt carried by an arm 17 of a member 13 or 14. The bolt 32 extends through an arcuate slot 34 formed in the lower portion of the arm 25 of a guide member. The nut 33 abuts against the inner face of the arm 25 for the purpose of maintaining the guide member in its adjusted position.

Formed integral with the low part 5 of the base 1, centrally thereof is a vertically disposed post 34 provided with a head 35 and a base 36. The lower end of the post 34 is integral with the end wall 9 of the element 4.

Secured upon the head 35 and extending inwardly therefrom is a combined retainer and fulcrum element 37 for the upper end of the set of cutting or sharpening blades. The lower face of the element 37 is formed with a recess 38 for the reception of the head 35. The element 37 is formed with an opening 39 through which extends a holdfast device 40 which engages with the post 34 for detachably securing the element 37 therewith. The lower face of the element 37 is provided with a substantially rectangular pocket 41 for the reception of the upper end of a set of cutting or sharpening blades. The pocket 41 has a pair of side walls 42, 43 and a pair of end walls 44, 45. The side and end walls of the pocket 41 are constructed in the same manner as the side and end walls of the pocket 6, therefore the end wall 44 of pocket 41 has a fulcrum point 46 and the end wall 45 a fulcrum point 47. The fulcrum points 46 and 47 are arranged in alignment with the fulcrum points 11, 12.

A set of cutting or sharpening blades is indicated at 49 generally and the number of the blades of the set can be as desired, but by way of example the set 49 is illustrated as consisting of five blades 50, 51, 52, 53 and 54. The blades are of oblong form and have squared edges. The blades 51 and 53 are of less width than the blades 50, 52 and 54. The blades 51 and 53 are alternately disposed with respect to the blades 50, 52 and 54. The upper end of the set of blades 49 is positioned in the pocket 41 and the lower end mounted in the pocket 6. The set of blades is mounted whereby it can bodily shift in opposite directions during the sharpening operation. The blade 50 of the set 49 has its outer side oppose the fulcrum points 11, 46 and bears thereagainst. The outer side of the blade 54 opposes the fulcrum points 12 and 47 and bears thereagainst. The set of blades 49 is so mounted that when a knife or shear blade is moved in one direction the set of blades will fulcrum on the points 11 and 46 and 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960

when moved in the opposite direction will fulcrum on the points 12 and 47.

The guide members 22, 23 are arranged relatively to the set of blades 47 to provide 5 passages 55, 56 for the positioning of the knife or shear blade when it is desired to sharpen the same. The guide members 22, 23 are arranged at an inclination relative to the set of blades 49 and are adjusted so that 10 the desired bevel with respect to the knife or shear blade will be maintained.

The cutting or sharpening blades are made of high tempered steel and are alternately arranged in the manner referred to 15 so as not to cut low places or hollows in the knife or shear blade while removing notches or broken places in the cutting edge of such blades.

The set of cutting blades is so mounted so 20 as to adjust itself to throw the square cutting edge of the blades of the set in a sharp cutting position.

The element 37 can be quickly detached 25 from the post 34 to enable the removing and replacing or changing of the position of the blades of the set. The cutting blades can be used on their four edges for the entire length thereof, by reversing the top of blade to the bottom and reversing back of blade to front 30 position. By this arrangement all the cutting edges of the blades can be placed in service. The blades are perfectly square on edges from top to bottom. The shifting positions in which the blades are placed provide 35 for the knife blade to control the cutting unit in serviceable position.

It is thought the many advantages of a 40 knife or shear blade sharpening device, in accordance with this invention can be readily understood, and although the preferred embodiment of the invention is as illustrated and described, yet it is to be understood that changes in the details of construction can be had which fall within the scope of the invention as claimed.

What I claim is:

1. A sharpening device comprising a bodily shiftable sharpening unit formed of a set of blades, the alternate blades of the set being 50 of the same width and of a different width than the width of the other blades of the set, a mounting for said set to provide for the fulcruming of the set for movement in opposite directions during the sharpening operation, and adjustable means opposing the 55 edges of the blades of said set to provide passages for the objects to be sharpened during the sharpening operation, said adjustable means being angularly disposed with respect to said set.

2. A sharpening device comprising a bodily shiftable sharpening unit formed of a set of blades, a mounting for the ends of said set to provide for the fulcruming of the set for 60 movement in opposite directions during the 65

sharpening operation, and bodily and angularly adjustable guiding means arranged at each side of the set and angularly disposed with respect thereto.

3. A sharpening device comprising a vertically disposed, bodily shiftable sharpening unit formed of a set of oblong, alternately disposed blades, the alternate blades being of the same width and of a different width than the width of the other blades of the set, 70 angularly adjustable guiding means opposing the lengthwise edges of said blades, and a mounting for the upper and lower ends of said set to provide for the fulcruming of the set for movement in opposite directions during the sharpening operation.

4. A sharpening device comprising a vertically disposed, bodily shiftable sharpening unit formed of a set of oblong, alternately disposed blades, the alternate blades being of the same width and of a different width than the width of the other blades of the set, angularly adjustable guiding means opposing the lengthwise edges of said blades, and a mounting for the upper and lower ends of said set to provide for the fulcruming of the set for movement in opposite directions during the sharpening operation, the mounting for the upper end of said set being detachably secured in position.

5. A sharpening device comprising a vertically disposed, bodily shiftable sharpening unit formed of a set of oblong blades, a mounting for the upper end of said set, said mounting provided with a pocket having the end walls thereof formed with aligning fulcrum points bearing against the sides of said set, a mounting for the lower end of said set including a pocket having its end walls formed with aligning fulcrum points bearing against the sides of said set, said fulcruming points providing for the bodily shifting of said set during the sharpening operation, and adjustable guides mounted adjacent the edges of said blades and angularly disposed with respect thereto.

6. A sharpening device comprising a pair of spaced, angularly disposed guide members, a vertically disposed, bodily shiftable sharpening unit formed of a set of opposed, oblong cutting blades having squared edges, and means enclosing the upper and lower ends of said set to provide for the fulcruming of the set for movement in opposite directions during the sharpening operation.

7. A sharpening device comprising a pair of spaced, angularly disposed guide members, a vertically disposed, bodily shiftable sharpening unit formed of a set of opposed, oblong cutting blades having squared edges, and means enclosing the upper and lower ends of said set to provide for the fulcruming of the set for movement in opposite directions during the sharpening operation, certain of said blades being of greater width than the 120 125 130

others, and the blades of greater width being alternately disposed with respect to the other blades.

8. A sharpening device comprising a pair of spaced, angularly disposed guide members, a vertically disposed, bodily shiftable sharpening unit formed of a set of opposed, oblong cutting blades having squared edges, means enclosing the upper and lower ends of said set to provide for the fulcruming of the set for movement in opposite directions during the sharpening operation, and means to provide for bodily shifting said guide members towards and from said set and for angularly adjusting said members relative to said set.

9. A sharpening device comprising a pair of spaced, angularly disposed guide members, a vertically disposed, bodily shiftable sharpening unit formed of a set of opposed, oblong cutting blades having squared edges, means enclosing the upper and lower ends of said set to provide for the fulcruming of the set for movement in opposite directions during the sharpening operation, certain of said blades being of greater width than the others, the blades of greater width being alternately disposed with respect to the other blades, and means to provide for bodily shifting said guide members towards and from said set and for angularly adjusting said members relative to said set.

In testimony whereof, I affix my signature hereto.

MARIAN A. MATTHEWS.
